(57) **CLAIM**

The ornamental designs for a drinking vessel with lid and straw, as shown and described.

DESCRIPTION

FIG. 1 is a perspective view of an embodiment of our design.

FIG. 2 is a top view of the embodiment.

FIG. 3 is a bottom view of the embodiment.

FIG. 4 is a front view of the embodiment.

FIG. 5 is a back view of the embodiment.

FIG. 6 is a right side view of the embodiment.

FIG. 7 is a left side view of the embodiment; and,

FIG. 8 is a perspective, exploded view of the embodiment. The broken lines depict portions of the drinking vessel with lid and straw that form no part of the claimed design.

1 Claim, 4 Drawing Sheets
